TIMER

William T. Bross, Cincinnati, Ohio, assignor to Liebel-Flarsheim, Cincinnati, Ohio, a corporation of Ohio
Filed Oct. 10, 1958, Ser. No. 766,541

11 Claims. (Cl. 74—665)

This invention relates to a dual purpose timing device for selectively determining the duration of an operation. More particularly the invention relates to a device having two rotary members, one for small units of time and the other for large units of time, both of which can be set to initiate an operation after a predetermined time interval, and following the predetermined interval, return to starting condition ready to repeat the interval of time. In the alternative, the present invention contemplates a timer which starting at zero may be used to time an operation and at the conclusion of the operation return to zero. In many types of operations, it is necessary to time an operation for a desired precise predetermined interval and to repeat that operation for the same precise interval of time. It is also desirable to have a timing mechanism in which the precise interval of time may be preselected and be altered in accordance with the necessities of differing situations. A precision interval timer preferably should be provided with means for setting units of time to provide a rough approximation of the desired interval and to provide means for setting fractional units of time to impart precision timing to a device.

The timer of the present invention includes two contact carriers, one driven at a slow speed for the large units of time and one driven at a faster speed which is a multiple of the speed of the other timer. Both contact carriers have contacts which cooperate with contacts on adjacent dials which may be set for the desired time interval. When there is simultaneous engagement of the contacts of both carriers, the time interval has been completed and an operation is either begun or terminated as the application of the device dictates. It is then necessary to return the contact carriers to their starting positions so that a timed operation can be repeated without requiring manual resetting of the timing instrument.

In accordance with the present invention the contact carriers are returned by means of torsion springs which are strained by the rotating movement of the contact carriers. The driving means associated with the contact carriers operates through clutches which disengage at the termination of the time interval. The disengagement of the clutches will permit the torsion springs to drive the contact carriers to their starting position. However, the design of the torsion spring carrier return system presents the problem to which the present invention is particularly directed. It will be appreciated that whereas one contact carrier moves through only one revolution, the faster contact carrier for fractional units will move through a plurality of revolutions. For example, in the device to be described in detail below, the fractional units carrier may be required to turn through up to 100 revolutions for one revolution of the units carrier.

Specifically then, the invention seeks to avoid the necessity of providing a torsion spring which will return a contact carrier equally effectively through a fraction of a revolution or through a large number of revolutions. Thus, a spring which could return the carrier through, say, 60 or 100 revolutions probably would be ineffective to return the carrier completely through a fraction of one revolution or would be too impractical to use because of the great size required to wind through 100 revolutions. Alternatively, a spring which, with surety would return the carrier through one revolution could not stand the

2

strain of winding through 60 or 100 revolutions as a practical matter.

An objective of the invention has been to provide, in a timer of the type described above, a torsion spring system for returning rotating contact carriers to their starting positions in which the torsion springs for each carrier are not strained in excess of one revolution.

It has been another objective of the invention to provide a torsion spring return for the contact carrier of a timer in which one end of the torsion spring is connected to the timer and in which the other end of the torsion spring is connected through a slip brake to the shaft about which the carrier rotates.

In a preferred construction, the invention comprises a timer having a contact carrier rotatably mounted on a shaft, a torsion spring connected at one end to the contact carrier, and a helical or torsion spring brake engageably mounted on the shaft and having one end thereof connected to the other end of the torsion spring, while the free end of the helical brake spring is engageable by the contact carrier to free the helical brake spring from the shaft and thereby disengage the brake. By virtue of this construction, as the contact carrier is rotated by its driving means, the torsion spring is strained sufficiently to be able to return the contact carrier to its starting position when the drive mechanism is released from the contact carrier, the helical spring brake maintaining one end of the torsion spring fixed to a shaft during the rotation of the carrier until the free end of the helical spring is engaged. At that time the carrier torsion spring and helical spring will move as a unit with the torsion spring being maintained in its strained condition. Thus, at any instant that the carrier is released from its driving means the torsion spring will be under sufficient stress to return the contact carrier to its starting position, but the additional stress on the torsion spring will never be greater than that imparted by full revolution of the carrier.

It has been another objective of the invention to provide a drive transmission for a timer of the type described in which a motor drives both contact carriers through reduction gearing and a pair of disk type clutches mounted on a shaft, an electromagnetic operator being provided to compress the assembly of gearing and clutches in an axial direction and thereby to cause the engagement of the clutches. An electromagnetically operated latch is associated with the operator to hold the clutches in engagement until the completion of a predetermined interval. The closing of the contacts on the carriers can, among other things, energize the latch magnet to release the latch and disengage the clutches, where upon the torsion springs will automatically return the contact carriers to starting position.

It has been still another objective of the invention to provide in a timer, means for rotating two contact carriers at a speed ratio of the order of 100:1. This speed ratio is obtained by providing a fixed gear and a rotatable gear adjacent the fixed gear. The rotatable gear is connected to the slow contact carrier and has a slightly different number of teeth from that of the fixed gear. A planetary gear, driven by the fast carrier drive rotates about the two adjacent gears causing the rotatable gear to move very slowly about its axis.

These and other objectives of the invention will be come more readily apparent in the following detailed description taken in conjunction with the accompanying drawings in which:

FIG. 1 is a perspective view of the timer constructed in accordance with the invention;

FIG. 2 is a cross-sectional view taken along lines 2—2 of FIG. 1;

FIG. 3 is a fragmentary top plan view of the invention; FIG. 4 is an exploded perspective view thereof; FIG. 5 is a fragmentary detailed view of the clutch operating mechanism; and

FIG. 6 is a cross-sectional view taken along lines 6-6 of FIG. 3.

The timer is mounted on a frame 10 having perpendicular posts 11 to which a shaft 12 is fixed mounted. At each end of the shaft 12 are rotatably mounted knurled dials 13 and 14 bearing indicia 15 and 16 respectively. The dial 13 is used to determine the units of time through which the timer operates and the dial 14 is used to determine the fractional units of time through which the timer operates. In the embodiment illustrated, the ratio of the dials is 100:1.

As best illustrated in FIG. 2, the dials each carry a pair of contacts 17 and 18 respectively which cooperate with bridging contacts 20 and 21 fixed to the contact carriers 22 and 23 respectively. The timer determines the completion of the prescribed interval of time by the simultaneous bridging of the contacts associated with the dials 13 and 14.

The bridging contacts 20 and 21 are semi-circular rings and the contacts 17 and 18 of each pair are spaced angularly by about 170° so that there is a closing of the contacts for each carrier over an interval of approximately 10°.

Referring to FIGS. 3 and 6, the contact carriers are driven at their respective speeds by a gear system including a gear 24 meshing with a gear 25 fixed to carrier 22, and a gear 26 engaging gear 27 fixed to carrier 23. The gears 24 and 26 are driven through clutches 28 and 29 respectively, which are operated by an axially movable hollow shaft 30 slidably mounted on a rod 31 (FIG. 6). The clutch 29 connects gear 26 to a gear 32 which is directly driven by a small gear 33 fixed to a shaft 34 driven by a synchronous motor (not shown). A planet gear 35 rotatably mounted on the gear 32 cooperates with a sun gear 36 fixed to rod 31 and having 99 teeth and a sun gear 37 having 100 teeth. Sun gear 37 is fixed on a journal bearing 38 which is rotatably mounted on rod 31. The cooperative action of planet gear 35 rotating about sun gears 36 and 37 provides a 100:1 gear reduction between gears 32 and 37. Since clutch 28 connects sun gear 37 to gear 24, the ratio of the speed of gear 26 to the speed of gear 24 is 100:1. Further, since the gear connection from gears 24 and 26 to their respective contact carriers is identical the contact carriers will have a 100:1 speed ratio.

It should be understood that the 100:1 ratio of contact carriers is specified, in part, to demonstrate the problems attending the return of a contact carrier to its starting position after it has rotated up to 100 revolutions. The invention, of course, has application to other systems utilizing differing ratios.

The clutches 28 and 29 each include a plate 40 fixed to the respective gears 24 and 26 to which they are connected and a plate 41. The plate 41 controlling gear 24 is fixed on journal bearing 38. The shaft 30 to which gear 24 and its clutch plate 40 are fixed is axially slidably in a post 42 at one end thereof, the rod 31 being mounted in a plate 43 at the other end of the assembly. A lever 44 pivoted at 45 to the post 42 bears against the shaft 30 as at 46 and is engaged at its other end at 47 by pins 48 fixed to a plate 49. The plate 49 is fixed to an armature 51 of an electromagnet 52 (FIG. 5). Energization of electromagnet 52 will move the plate 49 to the left to pivot the lever 44 in a clockwise direction to cause the clutches to engage; whereby the contact carriers may be driven at their 100:1 ratio. In its extreme left-most position a latch 53 spring biased in an upward direction engages a notch 54 in the plate 49, thereby holding the plate 49 in its left-most position against the action of the spring. The latch 53 is mounted on the armature 55

of a second electromagnet 56. Energization of electromagnet 56 pulls the armature downward to disengage the latch 53 from the notch 54, thereby releasing the pressure of plate 49 and lever 44 on the clutch plates.

Contact Carrier Return Mechanism

Contact carrier 22 has a pin 60 carried by the gear 25 which is fixed to the contact carrier 22. The pin 60 is connected to one end of a spirally wound torsion spring 61, the other end of which is fixed to a collar 62 which is in turn fixed by a set screw 63 to the shaft 12. Another pin 64 is carried by the gear 25 on the contact carrier 22 and cooperates with one of a pair of spring biased stops 65. The spring biased stop permits the pin to pass when the contact carrier is rotated in the normal timing direction but blocks the movement of the contact carrier when it is returned in the reverse direction under the action of the torsion spring. The position of engagement of the pin 64 with the stop 65 is the starting or zero position of the contact carrier 22.

It can be seen that when the clutch 28 is engaged and the timer gears are driven, the torsion spring 61 will be strained and will remain in the restrained condition brought about by rotation of the contact carrier 22. When the clutch 28 is disengaged, however, the contact carrier is free to rotate and under the action of the torsion spring will be driven around to its starting position and stop at that starting position by the engagement of the pin 64 with the stop 65. Since contact carrier 22 will normally rotate no more than one revolution, it is possible to utilize the comparatively simple torsion spring return described above.

Because the fractional units contact carrier 23 rotates through a plurality of revolutions before the carrier 22 completes a revolution, a more difficult problem of return is presented, requiring a different torsion spring returning system. The return system for carrier 23 includes a pin 70 fixed to the gear 27 by which carrier 23 is driven. A torsion spring 71 is fixed at one end to the pin 70 and at the other end to a collar 72. The collar 72 in this system, however, is freely rotatable with respect to the shaft 12 but is connected to shaft 12 by means of a helical brake spring 73 fixed at one end 74 to the collar 72. The brake spring, in its relaxed condition will have an inside diameter slightly less than the outside diameter of the shaft 12 whereby the spring will normally frictionally grip the shaft. The other end 75 of the brake spring extends radially outward from the shaft 12 to a position in which it is engageable by the pin 70. When the end 75 is engaged the spring will be strained in a direction to increase slightly its inside diameter whereby the brake spring can slip with respect to the shaft 12. A washer 76 spaces the end 75 of the spring from a snap washer 77 fixed to shaft 12 thereby preventing the leg 75 from becoming lodged in the open ends of washer 77. Washers 78 and 79 are loosely mounted on collars 62 and 72 respectively to maintain springs 61 and 71 in proper alignment. A pin 80 on gear 27, similar to the pin 64 on gear 25, cooperates with spring biased stop 65 so that the carrier is free for continued rotation in the driving or timing direction, but upon spring return, is blocked from passing the zero position.

The operation of the carrier return is as follows: when the clutch 29 is engaged and the gear 27 is being rotated by the drive means, the pin 70 will tend to tighten the torsion spring 71 and thereby to rotate collar 72. The tendency of the torsion spring 71 to rotate the collar 72 will be resisted by the tightening of the helical brake spring 73 on the fixed shaft 12. As the gear 27 continues to rotate, the pin 70 will be carried into engagement with the free end 75 of the helical spring and will tend to untwist the helical spring, thereby freeing it from its braking engagement with the shaft 12. The torsion spring will remain in the strained condition imparted to it by

the angular movement of the pin 70 but will not be strained further since the end of the torsion spring connected to the collar 72 will be rotated with the pin 70 for as many revolutions as are necessary to complete the timed interval.

At the completion of the timed interval, clutch 29 will be disengaged freeing the gear 27 and carrier 23 for rotation. The strain imparted to the torsion spring 71 will be sufficient to drive the contact carrier to its starting position at which pin 80 will strike stop 65 to bring the carrier to rest.

The timer unit described above is suitable for use with two different types of timing operations. For the one operation, the timer is set for a particular interval of time, started, and at the completion of the interval of time, the contacts of both carriers will be closed and the electromagnet 56 will be energized to unlatch and disengage the clutches. Depending upon the particular type of operation involved, other circuits may be energized by the simultaneous closing of the two sets of contacts for the operation of signal lights and the like.

In the other basic type of operation of the timer, the timer will be used for measuring time intervals. For example in the counting of the radiation of radio-active isotopes, a measure of activity can be obtained by determining the length of time a material emits a predetermined number of roentgens. With this type of operation, the timer would be set to zero and would be started when a suitable counter is exposed to the material being measured. When the counter has indicated that the radiation has reached the predetermined quantity, the timer motor would be stopped and the length of time read directly. Thereafter, by energizing the electromagnet 56, the carriers would be returned to zero through disengagement of the clutches under the action of the torsion springs thereby placing the timer in readiness for a new, similar operation.

In a general manner, while there has been disclosed in the above description, what is deemed to be the most practical and efficient embodiment of the invention, it should be well understood that the invention is not limited to such embodiment as there might be changes in the arrangement, disposition and form of the parts without departing from the principle of the present invention as comprehended within the scope of the accompanying claims.

Having described my invention, I claim:

1. In a timing device, a dial resetting mechanism comprising, a fixed shaft, a dial member rotatably mounted on said fixed shaft, a collar rotatably mounted on said fixed shaft, a torsion spring connecting said dial member to said collar, a slip brake connecting said collar to said shaft, and means for disengaging said slip brake when said torsion spring is strained through at least a portion of a revolution and maintaining the strain on said dial member, whereby said torsion spring will return said dial member to starting position upon completion of a timing operation.

2. In a timing device, a dial resetting mechanism comprising a fixed shaft, a dial member rotatably mounted on said fixed shaft, a collar rotatably mounted on said fixed shaft, a torsion spring connecting said dial member to said collar, a helical spring brake on said shaft and connected at one end to said collar, said brake gripping said shaft when said collar is urged by said torsion spring to rotate in the direction of said dial member and means for disengaging said brake when said torsion spring is strained through at least a portion of a revolution and maintaining the strain on said dial member, whereby said torsion spring will return said dial member to starting position upon completion of a timing operation.

3. In a timing device, a dial resetting mechanism comprising, a fixed shaft, a dial member rotatably mounted on said fixed shaft, a collar rotatably mounted on said

fixed shaft, a torsion spring connecting said dial member to said collar, a helical spring brake on said shaft and connected at one end to said collar, said brake gripping said shaft when said collar is urged by said torsion spring to rotate in the direction of said dial member and means on said dial member engageable with the free end of said spring brake to release said brake upon engagement of said free end, whereby said torsion spring will not be strained greater than one revolution of said dial member and will return said dial member to starting position upon completion of a timing operation.

4. In a timing device, a dial resetting mechanism comprising, a fixed shaft, a dial member rotatably mounted on said fixed shaft, a collar rotatably mounted on said fixed shaft, a torsion spring connecting said dial member to said collar, a helical spring brake on said shaft and connected at one end to said collar, said brake gripping said shaft when said collar is urged by said torsion spring to rotate in the direction of said dial member, means on said dial member engageable with the free end of said spring brake to release said brake upon engagement of said free end, whereby on said torsion spring will not be strained greater than one revolution of said dial member and will return said dial member to starting position upon completion of a timing operation, and means providing a slideable friction connection between said free end of said spring brake and said shaft to assure braking action.

5. In a timing device, a dial resetting mechanism comprising, a frame, dial member, means rotatably mounting said dial member on said frame, a torsion spring connected at one end to said dial member, a slip brake means connecting the other end of said spring to said frame and means for disengaging said slip brake means when said torsion spring is strained through at least a portion of a revolution and maintaining the strain on said dial member, whereby said spring will return said dial member to starting position upon completion of a timing operation.

6. In a timing device, a dial resetting mechanism comprising a frame, a dial member, means rotatably mounting said dial member on said frame, a torsion spring connected at one end to said dial member, means connected to the other end of said spring to cause said spring to be strained upon rotation of said dial member sufficiently to return said dial member to a predetermined starting position, said means preventing straining said torsion spring greater than one revolution.

7. A timing device comprising, a fixed shaft, a pair of timing members rotatably mounted on said shaft, drive means for rotating one of said members at a predetermined speed and the other of said members at a speed which is a predetermined multiple of said predetermined speed, clutches between said drive means and said members, a first torsion spring connecting said slower member to said shaft to return said member to starting position when said clutches are disconnected, a collar rotatably mounted on said fixed shaft, a second torsion spring connecting said faster member to said collar, a slip brake connecting said collar to said shaft, and means for disengaging said slip brake when said second torsion spring is strained no greater than one revolution and maintaining the strain on said second torsion spring whereby said torsion spring will return said faster member to starting position upon completion of a timing operation.

8. A timing device comprising, a fixed shaft, a pair of timing members rotatably mounted on said shaft, drive means for rotating one of said members at a predetermined speed and the other of said members at a speed which is a predetermined multiple of said predetermined speed, clutches between said drive means and said members, a first torsion spring connecting said slower member to said shaft to return said member to starting position when said clutches are disconnected, a collar rotatably mounted on said fixed shaft, a second torsion spring con-

necting said faster member to said collar, helical spring brake on said shaft and connected at one end to said collar, said brake gripping said shaft when said collar is urged by said second torsion spring to rotate in the direction of faster member, means on said faster member engageable with the free end of said spring brake to release said brake upon engagement of said free end, whereby said second torsion spring will be strained no greater than one revolution of said dial member and will return said faster member to starting position upon completion of a timing operation.

9. A timing device according to claim 8 in which said drive means and clutches comprises, a pair of coaxial timing member gears drivably engaging respective timing members, clutch plates on said gears, coaxial mating clutch plates mounted adjacent said gear clutch plates, a rotatable driving gear fixed to one of said mating clutch plates, a pair of coaxial sun gears disposed between said timing member gears, one of said sun gears being fixed, the other of said sun gears having a number of teeth different from that of said one sun gear and being fixed for rotation with the other of said mating clutch plates, a planet gear rotatably mounted on said driving gear and meshing with said sun gears, and means for effecting engagement of said clutch plates.

10. In a timer having a slow rotatable member and a

5
10

fast rotatable member, a system for driving said members at their proper relative speeds comprising, a pair of coaxial gears drivably engaging said rotatable members, clutch plates on said gears, coaxial mating clutch plates mounted adjacent said gear clutch plates, a rotatable driving gear fixed to one of said mating clutch plates, a pair of coaxial sun gears, having differing numbers of teeth, one of said sun gears being fixed, the other of said sun gears being fixed for rotation with the other of said mating clutch plates, a planet gear rotatably mounted on said driving gear and meshing with said sun gears, and means for effecting engagement of said clutch plates.

11. A system according to claim 10 in which clutch engagement means comprises means for compressing the above described assembly of gears and clutch plates together in an axial direction.
